UNITED STATES PATENT OFFICE.

DAVID R. KINYON, OF RARITAN, NEW JERSEY,

CHAIN-GUIDING BOX FOR CLOTH STRETCHING AND DRYING MACHINES.

SPECIFICATION forming part of Letters Patent No. 499,839, dated June 20, 1893.

Application filed September 5, 1892. Serial No. 445,097. (No model.)

To all whom it may concern:

Be it known that I, DAVID R. KINYON, a citizen of the United States, residing at Raritan, in the county of Somerset, State of New Jersey, have invented certain new and useful Improvements in Chain-Guiding Boxes for Cloth Stretching and Drying Machines, of which the following is a specification, reference being had therein to the accompanying drawings.

This invention relates to improvements in that class of tentering-machines in which the cloth is stretched between two chains which travel at a uniform rate of speed, and operate one on each side of the machine.

The object of my improvement is to provide the chain-boxes with simple, inexpensive, durable and efficient means for guiding the chain, which means shall be easily reversed, transposed and adjusted to increase the durability of said boxes. I attain this object by the construction illustrated in the accompanying drawings, in which—

Figure 1 represents a transverse vertical section of a portion of a tentering-machine provided with chain-boxes constructed in accordance with my invention. Fig. 2 is a side view of one of the boxes on a larger scale with a chain-link therein. Fig. 3 is a transverse vertical section of the chain-box with chain-link therein. Fig. 4 represents a chain-link in side and top view.

In said drawings A represents a portion of the frame of a tentering-machine carrying as usual, a certain distance apart, a series of rods B, each one having at one end a bevel pinion b meshing with a pinion on a horizontal line of shafting (not shown), by which a few rotations can be given to the rods to regulate the distance between the chain-carrying plates C retained by said rods in accordance with the width of the cloth k operated upon. For this purpose, the rods B have right and left hand screws cut thereon, that are received in nuts c secured to the plates C. To the top and bottom of said plates, the chain boxes are secured.

Each improved chain box consists of two angle bars D and D², retained at suitable distance apart by sleeves E and bolts e passing through said bars and sleeves, the inner bar D² being also secured to the flange on the edge of the plate C by means of bolts e² shown

in Fig. 1. The bars D and D² have their angular webs d turned away from the interior of the chain box, of which said bars form the top and bottom walls. To the face of each web d are adjustably secured the planed rectangular bars F, by means of bolts f passing through slots f² in said bars F and through perforations in the web d. The inner edges of the bars F are thus retained at a suitable distance from each other to maintain between them a slot F² for the free passage of the gill-plates g carrying the tentering-hooks g². Said gill-plates project from one side of the chain links G, which may be of any suitable construction. By having the slots F² in the bars F equidistant from the top and bottom edge thereof four distinct steel wearing surfaces 65 for the side of the chain are obtained consecutively from each bar. When the inside edge is worn, it can be turned to the outside, and when this side is worn, the bar can be turned upside down and its two sides used. 70 As the steel bars F are of rectangular form, they can be easily polished to present a smooth surface for the chain.

I am aware that English Patent No. 5,459 of 1889 shows double flanged cast bars retained together in pairs with their flanges turned toward each other to form chain boxes, and that said double flanged plates are reversible, but said boxes differ from mine in the location occupied by the flanges or webs 85 of the bars toward each other, and by the absence of any plain reversible rectangular bars as F, adjustably secured to the webs of the bars and constituting the wearing face of the chain box.

Having now fully described my invention, I claim—

In combination with the frame of a tentering machine, a chain box consisting of two angular bars having their vertical webs turned away from each other, sleeves and bolts therethrough to retain them united apart, and bars F adjustably and reversibly secured to the vertical webs of the angle-bars substantially as described.

In testimony whereof I affix my signature in presence of two witnesses.

DAVID R. KINYON.
